UNITED STATES PATENT OFFICE

2,010,094

PROPELLER

William H. Leinweber, Chicago, Ill.

Application January 21, 1933, Serial No. 652,829

1 Claim. (Cl. 170—170)

This invention relates to a propeller.

It is an object of this invention to provide an improved propeller which is relatively simple and inexpensive in construction and efficient in use.

5 Other objects will appear hereinafter.

The invention consists in the novel combination and arrangement of parts to be hereinafter described and claimed.

10 The invention will be best understood by reference to the accompanying drawing, showing the preferred form of construction and in which:

Fig. 1 is a perspective view of a preferred embodiment of the invention;

Fig. 2 is a sectional view on line 2—2 in Fig. 1;

15 Fig. 3 is an elevational view of the same; and

Fig. 4 is a top plan view thereof.

The new propeller comprises a hub 1 and blades 2 and 3 extending radially therefrom.

20 Formed integrally with, or converted in any suitable manner to, each of the blades, and extending transversely thereacross, is a series of fins 4. These fins 4 are curved throughout their extent and they have a convex curvature in the direction of the hub 1, or a concave curvature in the direction of the radially outer ends or tips 5 of the blades (Figs. 3 and 4); the height of the fins 4 increasing gradually from the leading edges 5 of the blades to the trailing edges 6 thereof.

25 The present propeller is especially designed for use as a ventilating fan and when in use improves

generally the circulation of the air in which it operates, one reason for this being that the construction of the fins 4 directs the air therefrom toward the radially outer ends or tips of the blades.

5 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

10 Having thus described my invention what I claim as new and desire to secure by Letters Patent, is:

15 A propeller including a blade having a series of fins extending transversely thereacross between the leading and trailing edges thereof; said blade having a substantially uniform and flat surface throughout its main extent on the side thereof on which the said fins are arranged; each of said fins being curved throughout its extent and having a concave curvature in a direction toward the radial tip of the blade; said fins gradually increasing in height from the leading edge of the 20 blade to the trailing edge thereof.

25 WILLIAM H. LEINWEBER.
